METHOD OF AND APPARATUS FOR
FORMING PACKAGES

Clarence W. Vogt, Norwalk, Conn.

Application December 2, 1949, Serial No. 130,729

14 Claims. (Cl. 53—6)

1

This invention relates to improvements in forming packages, and in particular to improvements in packaging objects or commodities in flexible or semi-rigid sheet materials.

It is an object of the present invention to provide an improved packaging method and apparatus which will produce finished packages at a higher rate than present commercial packaging machinery with a reduced cost per package and without requiring an undue increase in the size and cost of the apparatus.

Another object is to provide a method of and apparatus for forming packages which includes the feeding of a plurality of sequences of enwraps, the forming of open longitudinal receiving channels in each sequence of enwraps, the depositing of a corner edge of the objects to be packaged into a complementary shape of the channel, and the completing of an individual package surrounding each of the objects. In this way, each object may occupy a predetermined position with respect to this enwrapment, and each panel of the completed package may bear printed material, advertising, trademarks or the like at the desired predetermined location.

A further object is to provide a method of and apparatus for forming packages utilizing a plurality of sequences of enwraps which may be conjointly fed by a common mechanism, thereby simplifying the feeding of the enwraps and also materially simplifying the adjustment of the feeding mechanism to obtain accurate registry of each enwrapment.

Another object is to provide a method of and apparatus for forming packages which is so arranged and constructed that it may feed a pair of sequences of enwraps in parallel relation with the objects to be wrapped being handled and deposited alternately into the two packaging paths from a common mechanism.

A further object is to provide an improved packaging method and apparatus utilizing dual packaging paths with enwraps being intermittently advanced conjointly along said paths and objects to be wrapped alternately deposited in one of the paths at each cause between the successive advancements of the enwraps.

A still further object of the present invention is to provide a method of and apparatus for packaging composite objects by feeding enwraps and successively shaping the enwraps to provide trough-like channels for receiving and assembling the components of the objects and thereafter enclosing the composite objects to complete a package therearound.

2

Other objects and advantages will become apparent from the following detailed description accompanied by the drawings in which:

Fig. 1 is an elevational view showing in schematic form a preferred embodiment for carrying out the present invention;

Fig. 2 is a plan view of a section of sheet material to provide suitable enwraps for use in the apparatus shown in Fig. 1;

Fig. 2A is a sectional view of the sheet material shown in Fig. 2 shaped to suitable configuration for depositing objects thereon for packaging;

Fig. 3 is an enlarged elevational view of a mechanism for supplying and depositing the objects or commodities to be packaged;

Fig. 4 is a sectional view taken substantially on line 4—4 of Fig. 3;

Fig. 5 is an enlarged sectional view taken substantially on line 5—5 of Fig. 3;

Fig. 6 is an enlarged fragmentary sectional view taken substantially on line 6—6 of Fig. 3;

Fig. 7 is an enlarged sectional view showing a portion of a driving mechanism suitable for use in connection with the apparatus shown in Figure 1;

Fig. 8 is another elevational view of the mechanism shown in Fig. 7;

Fig. 9 is a perspective view of a completed package produced in accordance with the present invention;

Fig. 10 is a similar perspective view of another form of package which may be made in accordance with the present invention;

Fig. 11 is a fragmentary sectional view of a mechanism which may comprise an attachment to the apparatus shown in Fig. 1; and

Fig. 12 is a fragmentary sectional view of a modified form of mechanism for depositing objects or commodities to be packaged.

The present invention will be described in connection with the improved packaging of plastic material, such as for example, individual portions of ice cream or the like. However, it will be obvious that many other objects or commodities whether plastic or not, may be packaged in accordance with the principles of the invention. Composite objects requiring a plurality of depositions of component parts may also be assembled and packaged. For example, it is advantageous for use in the formation of packages enclosing and protectively retaining composite multiple layer confections such as ice cream sandwiches and the like. For the purpose of this description, the terms "plastic material" shall be construed to include materials which may be flowed

50
55

or forced through passages or conduits by the application of pressure, but which do not flow appreciably under the influence of gravity.

In the preferred embodiment of the invention illustrated in the drawings, packages may be formed by the following steps:

1. Two sequences of enwraps may be conjointly fed as a single web of sheet material with the individual enwrapping sections of each sequence positioned and arranged in offset or staggered relationship so that the mid-points of the enwraps of one sequence are opposite adjacent end portions of individual enwraps of the other sequences.

2. Prior to receiving the objects or commodities to be packaged, each sequence of enwraps may be shaped to provide longitudinally extending generally concave or trough-like receiving channels. These channels are open and have an apex which is adapted to receive a corner edge of the objects or commodities to be packaged so that when the objects are deposited they may be accurately positioned with respect to the edge portions of the enwrap. This results in a package in which the exterior design, printed matter etc., may be accurately registered in advance and each finished package will have a uniform appearance. This obviates the need for repetitive printing of enwraps presently utilized because of the inability of many present day wrapping machines to accurately position the enwraps with respect to the objects. It is believed that uniform packages having registered printing will provide a more attractive appearance of the finished package, thus making it more readily saleable.

3. The conjointly fed sequences of enwraps may be intermittently advanced with a suitable pause, hesitation or dwell between each advancement. This facilitates the proper depositing of the objects or commodities for packaging, in the case of plastic materials, many of which have a tendency to cling to surfaces with which they come in contact, the hesitation or dwell will permit the severance or removal of the plastic material from its feed mechanism to provide increased accuracy in the amount of each object deposited.

4. With the wrappers of each sequence offset with respect to each other, the intermittent feeding of the sequences of enwraps permits alternate deposition of an object in each sequence of enwraps at each pause or hesitation. Such an arrangement is beneficial in connection with the deposition of masses of plastic material since the plastic material may be fed from a single source with continuous flow which flow is diverted from one to the other of the sequences of enwraps for formation and deposition.

5. The sequences of enwraps may then be separated or severed along a line extending longitudinally between the sequences and individual packages may be formed to enclose or surround the objects deposited in each sequence of enwraps. The individual enwraps of each sequence may be separated or severed prior to, during, or after folding the enwraps about the objects. If desired, the enwraps may be folded to tubular form about the objects and suitable end folds made to enclose the object. Alternatively, sealed packages may be made by adhering together, preferably with heat and pressure, juxtaposed portions of the sheet material from which the enwraps are fabricated.

The sheet material to be used for forming packages may be fed as a single integral web, dimensioned and arranged to provide the desired number of sequences or series of enwraps.

5 Each sequence may be fed as a unit or, if desired, the sequences may comprise a series or plurality of separate enwraps. It is believed preferable to feed a single integral web on which the sequences of individual enwrap sections 10 may be suitably defined.

The sheet material may comprise any flexible or non-rigid sheet having the desired characteristics for packaging purposes. Examples of suitable sheet materials are papers of all kinds, regenerated cellulose, synthetic or plastic films, metallic foil and the like. It has been found that for many objects it is advantageous to utilize combinations of these sheet materials to obtain the properties desired. One component 15 may be selected for its strength or imperviousness and might be combined with another which provides a more decorative appearance when printed, or is capable of being heat-sealed. 20 Many such composite or laminated sheet materials are extremely beneficial. As will be seen, the present invention also makes possible the use of heavier, more rigid sheet materials or flexible materials which may be reinforced at desired locations. This means greater protection of the packaged commodity during handling and shipping and until the package is opened 25 by the consumer.

In the fabrication of the enwraps it may 30 be desirable to incorporate a number of aids to packaging in addition to the imprinting of designs, advertising material, manufacturer's name and address, trade-marks, etc. For example, score lines or fold lines may be provided 35 where the sheet material is subsequently to be folded and it may be desirable to incorporate adhesive spots, stripes or areas to permit the retaining of folds made in the package or to permit the making of hermetically sealed packages. 40 It is also contemplated that suitably located edge slits, tear strips, cut score lines, or other means 45 will facilitate the utility of the enwraps in the formation, closing, opening, etc., of the package.

50 Looking now at Figure 1, the numeral 1 denotes a supply roll from which a web of suitable sheet material may be withdrawn. The web may pass over a pair of idler rolls 2 being fed from the supply roll by suitable feed rolls 3. The feed rolls 3 may be driven by suitable source of rotary power (not shown) and may withdraw the web against the resistance of a friction brake and weight mechanism indicated by the numeral 4 and acting on the shape of the supply roll 1.

55 To maintain accurate registry of the web W, a suitable conventional adjusting means may be incorporated in the web feed mechanism. For example, a scanning mechanism indicated by the numeral 5, and including a photo-electric cell, 60 may operate to create an impulse when a scanning mark or registry indicia on the web passes across the field of the scanner. These marks may be placed on the web at the time that it is printed and are spaced to correspond to the length of individual enwrap sections. The 65 impulse created by the scanner may be amplified, compared with a standard and any necessary adjustments transmitted by known mechanisms to one or more of the feed mechanisms to assure 70 proper timing of the various portions of the 75

apparatus in accordance with the printed pattern on the web.

After passing through the feed rolls 3, the web may be associated with a slack take-up roll 6 which is resiliently urged by a spring 7 into contact with the web to maintain it in a taut position. The web may then pass over an intermittently operated feed roll 8 and may be maintained in the desired frictional engagement with the feed roll 8 by a pressure roller 10 which may be freely rotatable or power driven in timed relation with the roll 8 and prevents any slippage backward of the web with respect to the feed roll 8. With the feed rolls 3 operating continuously and the roll 8 operating intermittently, it may be seen that the web will be drawn into a loop by the roll 6 when the roll 8 is not moving, and this loop will disappear when the roll 8 is actuated to drive the web.

If the rolls 8 and 10 grip the web with a relatively light pressure and are driven to advance a length of web greater than the amount of the loop, they will advance the web against the pressure of the resilient slack roll 6 until the loop is eliminated and will slip over the web thereafter, but will maintain the desired tension in the web at all times.

From the intermittently operated feed roll 8, the web W passes into contact with a suitable former 11 which causes the web to assume the configuration illustrated in cross section in Fig. 2A. The former 11 is a conventional type of shoe or mandrel designed to be interposed in the path of travel of the web so that as it is slid over the surface of the former, the web is caused to assume the desired configuration. Each sequence of enwrapsments is shaped to provide a longitudinally extending receiving channel, indicated by the numeral 9. The channels 9 have angularly directed faces which converge to an apex and the bottom portion of the channel is complementary shaped to correspond to a corner edge of the object or commodity to be received therein. Accordingly, each object will be accurately and precisely located with respect to the edges of its enwrapment and also with respect to the printed matter carried by the enwrapment.

While in the form of the invention illustrated, the objects are indicated as being rectangular or square in cross section with the channels 9 correspondingly shaped, it may be seen that many other shapes of objects may be packaged to advantage by the present invention. Objects which have a round, triangular, hexagonal or even some irregular cross-sectional configuration may be utilized, the primary feature being that they have a corner edge which may be positioned in a complementary receiving channel to cause the object to assume a predetermined position.

During and after the shaping of the web, it may be contacted and driven by an upper friction belt 12 carried by suitably spaced pulleys or rollers 13 and guided to the desired path such as by guide rolls 14. The web may also be simultaneously contacted by a lower friction belt 15 entrained around suitable pulleys or rollers 16. The belts 12 and 15 are preferably driven intermittently in timed relation with the feed roll 8 and pressure roll 10. While the web is being advanced by the belts 12 and 15 which grip it in centrally disposed portions thereof, other portions of the web may be supported by surfaces of members 17 mounted on the frame of the apparatus to permit the web to be slid therealong.

Fig. 2 is a plan view of a portion of a preferred

form of web of sheet material for use in the present invention. This form of web is disclosed in my copending application Serial No. 120,942, filed October 12, 1949, and entitled Sequences of Enwrapsments, now abandoned. The web is defined into a pair of sequences of enwrapsments by a longitudinally extending centrally disposed dash dot line 18 defining the common border between the pair of sequences of enwrapsments. Each sequence of enwrapsments may also be defined into individual enwrapment sections by dash dot lines 20 which extend along the common boundary between adjacent enwrapment sections. In addition, the web may be provided with prefabricated score lines or fold lines indicated by numeral 21 which lines may be positioned at the location of folds to be made during formation of the package and may be creased or scored to facilitate the formation of such folds. The prefabrication of the fold lines 21 defines the side panels of the completed package which will fall between these fold lines. Thus, it is possible to provide in advance, printed matter over the areas of the side panels, such as, for example, within the rectangles 25 defined by dash lines 22. These rectangles will be accurately registered on each side panel of the package and the object or commodity to be packaged will occupy a predetermined position with respect to the margin of each enwrapment and with respect to the printed matter disposed on the enwrapment.

As indicated by the numeral 23, a part of the common boundary 20 between adjacent enwrapsments of a sequence, may be slit at the time the enwrapsments are fabricated for a purpose which will be subsequently described. The slitting of the edge portions of the web may also be accomplished by the web feed means. For example, one of the feed rolls 3 may be provided with slitter elements 19, appropriately spaced and dimensioned to produce the slits 23 at opposite edges of the web.

To facilitate opening of the completed package, particularly if it is to be heat sealed, each sequence of enwrapsments may be provided with a tear strip indicated by the numeral 24 and disposed in the region where the heat seal will be formed. It is conventional practice to adhere such tear strips in a position where they may be pulled by the consumer to tear open the sealed portion of the enwrapment and facilitate access to the contents of the package. The application and adhering of the tear strips is indicated in Fig. 1. The tear strips may be supplied from a roll 25 and rolled onto the web after being provided with adhesive areas by applying the glue in the conventional manner or by heat activating a thermoplastic adhesive disposed on the surface of the tear strip. A roller 26 which may be driven or may be freely rotating is shown as positioned adjacent the periphery of one of the feed rolls 3 to apply and press the tear strip 24 to the web W at the desired location.

As previously described, it is preferable that the web W be intermittently advanced and to accomplish this the feed roll 8 and the belts 12 and 15 may be driven in timed relation by any suitable driving mechanism to provide the desired characteristics. Figs. 7 and 8 illustrate an excellent mechanism for obtaining appropriate intermittent advancement of the web. As shown in Fig. 7, one of the rollers 13 for the belt 12 may be mounted for rotation on a shaft 27 which also carries a gear 28. This gear 28 meshes with and drives a gear 30 carried for rotation by a shaft 31

on which is mounted one of the rollers 16 for driving the lower belt 15.

The shaft 27 also carries a worm wheel 32 as may best be seen in Fig. 8. Meshing with and driving the worm wheel 32 is a worm 33 which is mounted for rotation on a driving shaft 34. While the worm 33 is fixed to rotate with the shaft 34 it is also mounted so that it may move axially along the shaft 34 even during rotation. This may be done by mounting the worm on the shaft by an axially extending spline or key 35. The shaft 34 also carries for rotation a cylindrical or barrel cam 36, mounted for rotation on the shaft 34 by the spline or key 35, but capable of axial movement therealong. The worm 33 and the cam 36 are secured together so that their axial movement is identical. The periphery of the cam 36 is provided with a suitably shaped cam track 37 and disposed within the cam track is a roller follower 38 carried by a stationary support member 40. Thus, as the shaft 34 rotates, the cam 36 and worm 33 will move axially along the shaft 34 as dictated by the cam track 37 and roller follower 38. It may be seen that if the cam track 37 angles in a direction approaching the lead angle of the worm 33, the cam and worm will move axially along the shaft and the worm will not exert its full driving effect to the worm wheel 32. This means that the shaft 31 and accordingly the pulley 16 will move at a decelerated speed. However, since the cam track 37 has a closed course, returning to its initial position during each revolution of the shaft 34, the cam track must angle in the opposite direction, causing the worm 33 to drive the worm wheel 32 and the pulley 16 at an accelerated speed. By varying the angularity and the arcuate extent of the angular portions of the cam track 37, almost any desired characteristics of motion of the driven shafts 27 and 31 may be obtained. For example, the shafts 27 and 31 may be caused to dwell for as much as about three-quarters of each revolution of the driving shaft 34. By forming the cam 36 with an appropriate cam track 37, the shaft 34 may be driven with any source of rotary power, moving at a constant rate, and the shafts 27 and 31 will move intermittently with the desired characteristics.

The pulleys 16 and 13 driving the belts 15 and 12 respectively may be mounted so that the belts engage the web W therebetween with the desired pressure. Such pressure may be adjusted and be resilient so that the belts will advance the web until the web has a predetermined tension, and will thereafter slip. This means that the feed rolls 3 which may be operated at a constant speed will withdraw and advance the desired amount of web as controlled by the scanner mechanism 5 and its associated registry adjustment mechanism. The intermittent advancing movement of the belts may be slightly more than the desired advancement of the web and the web will be retained taut and in proper engagement with the former 11. The intermittently operated feed roll 8 may be driven from the shaft 27 so that it will operate in proper relation with the belts 12 and 15.

At a point along the path of movement of the web after the longitudinally extending receiving channels 9 have been formed, the objects or commodities to be packaged may be deposited into each of the channels by any suitable mechanism. It is preferable that the objects be placed on the web with a corner edge of each object

received in the complementary shape at the apex of the receiving channel.

A number of depositing mechanisms may be used to place a wide variety of objects on the web. Very good results may be obtained by the use of apparatus for producing measured masses of plastic material such as is shown and described in my co-pending applications, Serial No. 123-575, filed October 26, 1949, entitled Apparatus for and Method of Producing Plastic Masses; and Serial No. 126,213, filed November 8, 1949, entitled Production of Accurately Measured Plastic Masses, now U. S. Patent No. 2,666,229.

For purposes of illustration, the drawings show a simple mechanism for feeding and depositing objects, such as individual servings of plastic ice cream. Such a material may be made in a continuous process apparatus and will be delivered therefrom through a conduit under pressure. Fig. 3 indicates a pair of conduits 41 and 42 which may lead from a pair of continuous process units to feed two different flavors of ice cream in a partially frozen, plastic state.

These supply conduits 41 and 42 terminate in a suitable header or manifold 43 which as shown in Fig. 4 leads to two branches 44. Between the junction of the conduits 41 and 42 with the header 43, and extending substantially centrally through each of the branches 44 is a partition 45 so that the two flavors from the conduits will flow in side by side divided relation through each of the branches. Each of the branches 44 terminates in a forming aperture or nozzle 46 at which point the partition 45 also terminates and the two flavors on leaving the nozzle merge to provide a composite mass or portion of the plastic material.

To control the flow of plastic material from the forming apertures and to cause alternate deposits onto each of the packaging paths, a mechanism for shutting off the flow at each of the nozzles is provided. Such a mechanism is illustrated in Fig. 5. Briefly this mechanism comprises a pair of sliding shutter members 47, mounted for movement through an opening in the wall of each of the branches 44 in the region of the nozzle 46. These members 47 also pass through slots in the partition 45 and the walls of the slots may serve to guide and support the members as they are moved. Preferably the shutters 47 are actuated in timed relation with each other from a common mechanism so that as one is closed the other is opened. This may be accomplished by providing each of the shutter members with a pin 48 which is received in a slot formed in an oscillating arm or rod 50. Each of the rods 50 is carried by a rocker shaft 51, which shafts also carry gears 52. The teeth of the gears 52 are in mesh with spaced portions of a driving rack 53 which is reciprocated by any suitable mechanism (not shown) in timed relation with the balance of the apparatus. The partition 45 is situated in position to form a pair of streams of plastic which have a triangular cross section and result in a rectangular or square two flavor portion. Obviously, this partition could be modified to form other arrangements, such as, horizontal or vertical layers, etc. The arrangement and movement of the partition 45 and the shutters 47 in Fig. 5 is best suited for single flavor portions of ice cream. To avoid smearing or intermixing of the flavors, the partition should be in a plane parallel to the direction of motion of the shutter members.

Since the plastic materials, such as ice cream,

have a tendency to cling to surfaces with which they come in contact, deposition of the individual portions may best be obtained if each portion is sheared or wiped or severed from the end face of the forming aperture or nozzle. To accomplish this, a severing mechanism, best illustrated in Fig. 6, may be utilized. Such a mechanism may comprise a suitable blade or knife 54 mounted at the end face of each of the nozzles and adapted to move through a path which will shear the plastic material extending from the nozzle and cause it to be cleanly deposited onto its enwrapment.

With the nozzles shaped as shown to produce a portion having a square or rectangular cross section, it is believed preferable to drive the blade or knife so that its tip follows a generally circular path in passing around the end of the nozzle. This may be done by mounting each of the blades on a pair of crank arms 55 carried for rotation by shafts 56. Each of the shafts 56 carries a gear 57 which meshes with and may be driven by an intermediate gear 58 mounted for rotation on a shaft 60. It may be seen that during half a revolution of the driving shaft 60 the blade will descend across the opening of the end face of the nozzle and during the other half a revolution the blade will return to its starting position with the blade and its tip ascending exteriorly of the nozzle opening. The blades may be intermittently driven so that they make a shearing stroke and return to dwell while poised above the nozzle or may rotate continuously, preferably with an accelerated cutting stroke and a decelerated return stroke.

The shaft 60 may be driven in proper timed relation with the balance of the mechanism so that it is actuated to shear plastic extending from the nozzle shortly after the shutter member 47 is closed to stop the flow. At the time that the blade 54 is actuated the web is preferably stationary with an enwrapment section suitably positioned beneath the nozzle to receive the portion to be deposited. The plastic may be deposited inwardly from the marginal edge of the wrapper (defined by the dot dash line 20 in Fig. 2) with the sheared end spaced from the slit edge portion 23 of the enwrapment by a distance equal to the amount of sheet material required to provide end folds for the package.

The provision of the edge slits 23 permits each of the blades 54 to pass through the path of the web W causing the end fold portions of the enwrapment in this region to be bent or flanged downwardly and outwardly against the blade. The position of the end fold portions of the enwrapment when wiping of the blade occurs is indicated by the numeral 61 at the right hand portion of Fig. 6. This flanging action is exaggerated in the drawing for clarity and is permitted by the clearance between the underside of the nozzle and the web. It may be noted that the interior surface of the blade may be caused to wipe itself clean against the end face of the nozzle, while the opposite surface of the blade will be wiped clean against the end fold portions of the enwrapment.

During the deposition of objects onto the web of enwrapments it may be desirable to provide additional support for the web in the region of the receiving channels 9. Such additional support may be in the form of stationary supporting surfaces, endless conveyors, or may be one or more series of movable support members positioned so that they will underlie the web and the objects which have been deposited. The pro-

vision of such additional support is also advantageous in that it may be useful for conveying the objects or commodity through the folding and closing operations necessary to complete the package.

In the drawings, a plurality of support members 64 are shown, mounted for movement in endless paths on a chain 65. A similar series of support members may be provided for each sequence of enwrapments. If desired, the support members may be provided for individual movement in a direction, perpendicularly to that of the path of the chain. This may facilitate proper positioning of the support members, at the time of deposition of the objects or commodity, or provide for movement during packaging operations.

Each of the chains 65 may carry a plurality of fixtures 66 provided with pins 67. The support members 64 carry stems which are slotted to receive the pins 67 and permit movement of the members 64 with respect to the chain. A follower 68 is carried by the stems of the support members to control the position of the members in co-operation with a cam surface 70 which may have the required configuration to locate the support members at the desired positions.

After the objects to be packaged have been deposited onto the enwrapments, it is only necessary to sever the web and complete the packaging by enclosing the enwrapments around the objects to form individual packages. It is first necessary to divide the web to separate the various sequences of enwrapments and in the form above shown this may be readily done by slitting the web along its longitudinal center line indicated by dot dash line 18 which forms a common boundary between the two sequences of enwrapments. Fig. 1 shows a rotary slitter 12 operating in conjunction with backup or platen roller 13, and this slitter mechanism may be driven in timed relation with the travel of the web.

After severing or separating the two sequences of enwrapments each sequence may be additionally handled to complete a package about each of the objects. The specific details of completing the packages are not considered essential to the present invention, since a number of conventional package forms may be created. Fig. 9 illustrates a desirable form of package which may be made from one of the enwrapments shown in Fig. 2. To obtain this type of package, opposite edge portions of the enwrapment may be folded over to close the enwrapment to tubular form about the object, with marginal edge portions indicated by the numeral 74 in Figs. 2, 6 and 9, extending outwardly from the package in contiguous relation. The contiguous edge portions of the enwrapment are preferably coated with a suitable adhesive material such as a thermoplastic adhesive and such marginal edges may be sealed together to provide what is known as a fin type seam, extending longitudinally along the tube. The folding of the sequence of enwrapments about the series of objects deposited at proper spaced intervals along the sequence may be progressively accomplished by conventional tube forming means with the marginal edges 74 placed in engagement with each other. This tubular portion of the sequences of enwrapments may be of sufficient length to include a number of the objects to be packaged, and in this way a continuous sealer such as a pair of heated pressure rollers, may be employed to effect the longitudinal seam.

At the region between successive objects suit-

able end closures may be formed to permit separation into individual packages. First the longitudinally extending fin seam may be folded down on to a side panel of the object (see Fig. 9) and the tube flattened in the region between adjacent objects. If desired, the opposed wall portions of the tube may be tucked just prior to flattening and sealing the tube, in a manner similar to that shown in my issued Patent 2,156,466, dated May 2, 1939. The flattened and sealed portion may then be cut or severed at the margins between the individual enwrapment sections so that a part of the sealed portion is disposed on each of the two adjacent packages.

Another package form is illustrated in Fig. 10, and in this instance the opposite marginal edge portions 74 of the enwrapment are overlapped to provide what is known as a lap seam, indicated by the numeral 75 in Fig. 10, which may or may not be heat sealed as desired. The sequence of enwrapments may be cut into individual sections and conventional end folds made to complete the package to the form shown in Fig. 10.

Fig. 11 illustrates a mechanism which may be used in conjunction with the apparatus shown in Fig. 1 and is particularly adapted for the assembly and packaging of composite objects, such as ice cream sandwiches. The particular attachment provides for the deposit of the wafers which form the top and bottom layers of the sandwich. Obviously two such attachments are required one being located ahead of the supply pipes 41, 42 and the header 43, and the other being located after the depositing mechanism. In the form shown, which is diagrammatic, a single feed mechanism which supplies wafers alternately for each of the two packaging paths is illustrated. Such mechanism comprises a hopper or supply tube 80 containing a plurality of wafers 81 in stacked relation. At the lower end of the hopper a slide member 82 is mounted to move transversely of the two packaging paths, being actuated by a lever 83 pivotally connected to the slide and having a fixed pivot point 84. The slide member 82 is provided with a pair of spaced apertures 85, each of which is slightly larger than the outline of a wafer and the thickness of the slide member is slightly less than the thickness of the wafers. Beneath the slide member are a pair of outwardly inclined chutes 86 which lead to the apex of the receiving channels 9 of the web. In the full line position of the slide member one of the apertures 85 is aligned with the stack of wafers so that a wafer is disposed within the aperture and supported by a bottom portion 87 of the hopper. When the slide member is moved by the lever 83 from its full line position to its dash and dot outline, the aperture which contains a wafer is moved to the right when viewing Fig. 11 and is deposited down the chute 86 and onto the formed web. At the same time the other of the apertures 85 in the slide member 82 is aligned with the stack of wafers and a wafer is positioned therein. Subsequent return movement of the supply member and lever to the left, when viewing Fig. 11, will cause the slide member to deposit the wafer in the left hand receiving channel. After deposit of an individual portion of ice cream from the forming aperture 46 additional wafers may be superposed to provide the composite articles, which may then be enclosed, as described, to provide completed packages.

Fig. 12 illustrates a modified form of depositing mechanism which is mounted above the

shaped web of enwrapments as was described in connection with the depositing mechanism shown in Fig. 5. In this form of the invention, objects are fed and deposited in a direction extending transversely of the longitudinal receiving channels 9. This is considered especially desirable for assembling and packaging items such as multilayer confections and the like. A supply conduit 98 leads from a suitable source of the commodity to be packaged and the flow may be alternately directed by an oscillating valve 91 to one or the other of a pair of forming apertures or nozzles 92, which are downwardly and outwardly directed toward the receiving channels of the web of enwrapments.

The oscillation of the valve 91 alternately opens the passage through the valve to permit substantially continuous flow of the plastic material, so that the masses may be deposited into one or the other of the packaging paths. Preferably the web of enwrapments is intermittently advanced and the deposition can be caused to occur during the hesitation or dwell of the web. To facilitate the deposition a pair of blades 93, which are similar to the blades 54 in the form of the invention shown in Fig. 6, may be mounted adjacent and in the plane of the end faces of the nozzles. These blades may be driven in timed relation with each other by a mechanism similar to that shown in Fig. 6. As indicated in Fig. 12, the web of enwrapments may be shaped to provide portions of the web, indicated by the numeral 94, for wiping engagement with the blade and such portions 94 may be slightly bowed so as to resiliently urge them into wiping contact with the blades. This form of the invention is considered beneficial for many plastic commodities. Where it is desirable to shear or wipe the plastic material at the time of deposit, an excellent wiping action can be obtained without providing the edge slits 23 on the web as shown in Fig. 2 for the form of the invention shown in Figs. 1 through 6.

An extremely satisfactory way of forming packages in accordance with the present invention is to utilize a web of packaging material with two sequences of enwrapment sections defined thereon and arranged in staggered relation with the midpoints of enwrapments of one sequence opposite to the end portions of adjacent enwrapments of the other sequences as shown in Fig. 2. The web is then advanced adjacent the receiving station with an intermittent motion, each forward motion of the web being for a distance equal to one half a wrapper length. At each pause or dwell of the web, an object may be deposited alternately in the appropriate one of the two packaging paths. When the objects being packaged comprise masses of plastic material, this arrangement facilitates the packaging operation since the plastic may be continuously flowed from a common source of supply and individual masses removed from the flow, accurately measured, and cleanly deposited. After deposition, the two sequences will contain the objects to be packaged in staggered relation (see Fig. 2 of my previously identified copending application Serial No. 120,942).

Until the web is severed into individual sequences of enwrapments, it may be fed by a common mechanism and provides higher capacity of completed packages without a corresponding increase in the amount of apparatus. Further, the web, as described is wider and the supply rolls therefor may be of greater diameter and permit

13

longer operation between changes to replenish the supply. In the case of commodities furnished for packaging from a continuous fabricating operation, each shutdown of the packaging operation may seriously affect the character of the commodity and thus be more costly than merely the expense of shutting down the fabricating apparatus.

The present invention provides a method of and apparatus for producing an increased number of packaged objects in a stated time and thus reduces the unit cost of each package, without unduly increasing the amount of apparatus required. The resulting packages will all be uniform and attractive in appearance. Each object may be accurately located with respect to its wrapper and with respect to the printed matter on the wrapper.

It will be appreciated that in the drawings, proportions have been exaggerated in some instances to provide a greater understanding of the invention.

It will be understood that the foregoing description of preferred embodiments of the invention is for the purpose of explanation and illustration, and numerous variations and modifications other than those which have been described may be made without departing from the spirit of the invention.

What I claim is:

1. The method of packaging which comprises feeding enwraps in a plurality of paths simultaneously continuously feeding material to be wrapped and extruding the same alternatively through a plurality of apertures, separately forming a plurality of series of objects to be wrapped from the extruded material, alternately depositing the objects of the said series so formed upon the enwraps in said paths, and forming individual packages enclosing each of said objects.

2. The method of packaging which comprises feeding enwraps in a plurality of paths, simultaneously continuously feeding a single flow of material to be wrapped, directing the material successively into a plurality of paths and separately forming a plurality of series of objects to be wrapped in such paths, alternately depositing the objects of the said series so formed in spaced relation upon the enwraps in said paths, and forming individual packages enclosing each of said objects.

3. The method of packaging which comprises feeding a plurality of spaced sequences of enwraps in given spaced paths, simultaneously continuously feeding a single flow of material to be wrapped, directing the material successively into a plurality of paths coextensive with the spaced paths of enwraps and forming objects to be wrapped in said paths, depositing the objects so formed in spaced relation upon the sequence of enwraps, and forming individual packages enclosing each of said objects.

4. The method of claim 3, wherein the enwraps of the spaced sequences are in staggered relation and wherein the formed objects are deposited alternatively in the respective sequences.

5. The method of packaging which comprises feeding enwraps in a plurality of paths, forming said enwraps into the form of channels each channel having a bottom edge, simultaneously continuously feeding material to be wrapped, separately forming a plurality of series of objects to be wrapped from the continuously fed material each of said objects having a bottom edge alternately depositing the objects of the said

14

series so formed upon the enwraps with the bottom edge of each object conforming to the bottom edge of a channel, and forming individual packages enclosing each of said objects.

6. The method of packaging which comprises feeding a plurality of sequences of enwraps in a plurality of respective paths, simultaneously continuously feeding material to be wrapped, forming the material into objects to be packaged, alternately depositing said objects onto the plurality of sequences of enwraps and forming individual packages enclosing each of said objects.

7. The method of claim 6 wherein the feeding of the enwraps includes the step of forming a pair of spaced parallel longitudinally extending channels in the said respective paths and the feeding thereof is accomplished by advancing the same for a distance equal to half an enwrapment length followed by a pause between each advancing motion, and wherein the objects are alternately deposited in the channels during the successive pauses.

8. Apparatus for forming packages comprising means for feeding enwraps in a plurality of paths, means for continuously feeding material to be wrapped, means to form a plurality of series of individual objects to be wrapped from the continuously fed material and for depositing said objects alternately upon the enwraps in said paths, and means to apply the enwraps about the objects to form individual packages enclosing the objects.

9. Apparatus for forming packages comprising means for feeding a plurality of spaced sequences of enwraps in given spaced paths, means for simultaneously continuously feeding a single flow of material to be wrapped, means for directing the material successively into a plurality of paths coextensive with the spaced paths of enwraps, means for forming objects to be wrapped from the material in the last named paths, means for depositing the objects so formed in spaced relation upon the sequence of enwraps, and means forming individual packages enclosing each of the objects.

10. Apparatus for forming packages comprising means for feeding a plurality of spaced sequences of enwraps in staggered relation in given spaced paths, means for simultaneously continuously feeding a single flow of material to be wrapped, means for directing the material successively into a plurality of paths coextensive with the spaced paths of enwraps, means for forming objects to be wrapped from the material in the last named paths, means for depositing the objects so formed alternately and in spaced relation upon the sequence of enwraps, and means forming individual packages enclosing each of the objects.

11. Apparatus for forming packages comprising means for feeding enwraps in a plurality of paths, means to form the enwraps into the form of spaced apart channels having a bottom edge, means for simultaneously continuously feeding material to be wrapped, means to form from the material a plurality of objects in spaced relation with bottom edges, means to deposit the objects so formed alternately upon the enwraps with the bottom edge of each object conforming to the bottom edge of the channels, and means forming individual packages enclosing each of the objects.

12. Apparatus for forming packages comprising means for feeding a plurality of sequences

15

of enwraps in step-by-step fashion in a plurality of respective paths, means for simultaneously continuously feeding material to be wrapped, means for forming the material into a plurality of paths of objects to be wrapped, means for alternately depositing said objects onto the two sequences of enwraps during the respective intervals of pause in the step-by-step motion, and means forming individual packages enclosing each of said objects.

13. Apparatus, according to claim 9, wherein means is provided to engage the material of the enwraps intermediate the sides thereof to move the enwraps through the aforesaid paths.

14. Apparatus, according to claim 11, wherein a plurality of movable supports are provided with supporting surfaces corresponding to the shape of the channels formed in the enwraps to support the objects deposited therein, and means to advance the supports in synchronism with the motion of the enwraps.
